DOOR KNOCKER

James M. Crowson, Abilene, Tex.

Application May 16, 1955, Serial No. 35,993

Term of patent 14 years

(Cl. D10—7)

Fig. 1 is a perspective view of a door knocker, showing my new design,

Fig. 2 is a rear, elevational view of the door knocker, Fig. 3 is a top, plan view of the door knocker, and Fig. 4 is an underside, plan view of the door knocker.

The characteristic features of the design reside in the portions shown in full lines.

I claim:

The ornamental design for a door knocker, as shown and described.
